UNITED STATES PATENT OFFICE.

WILLIAM F. SCHLEICH, OF NEW YORK, N. Y., ASSIGNOR TO SCHLEICH STUDIOS, INC.,
OF NEW YORK, N. Y., A CORPORATION OF NEW YORK.

DESIGN FOR A BIRD CAGE.

Application filed August 23, 1924. Serial No. 10,537. Term of patent 14 years.

To all whom it may concern:

Be it known that I, WILLIAM F. SCHLEICH, a citizen of the United States, residing at New York, in the county of Bronx and State of New York, have invented a new, original, and ornamental Design for Bird Cages, of which the following is a specification, reference being had to the accompanying drawing, forming part thereof.

The figure is a view in elevation of a bird cage showing my new design.

I claim:

The ornamental design for a bird cage, as shown.

WILLIAM F. SCHLEICH.
